ANTOINE LOUIS LAMBERT, OF CONCORDIA, KANSAS.

CREDIT-ACCOUNTING APPLIANCE.

1,030,785.

Specification of Letters Patent. Patented June 25, 1912.

Application filed August 15, 1911. Serial No. 644,158.

To all whom it may concern:

Be it known that I, ANTOINE LOUIS LAMBERT, a citizen of the United States, and a resident of Concordia, in the county of

Cloud and State of Kansas, have invented 5 a new and Improved Credit-Accounting Appliance, of which the following is a full, clear, and exact description.

The object of the invention is to provide 10 a new and improved credit-accounting appliance more especially designed for the use of merchants, to keep the accounts of customers who buy on credit in a very simple and accurate manner, to allow a salesman 15 to readily ascertain the customer's account, and to permit such salesman to make additions to the customer's account. For the purpose mentioned, use is made of a receptacle provided with an index for containing 20 the names of the customers, and indicating characters, and a rack in the said receptacle provided with pivoted bill holders having their indicating characters corresponding to the ones on the index.

25 A practical embodiment of the invention is represented in the accompanying drawings forming a part of this specification, in which similar characters of reference indicate corresponding parts in all the views.

30 Figure 1 is a perspective view of the credit-accounting appliance in open position; Fig. 2 is a side elevation of the same in closed position and the receptacle shown partly in section; Fig. 3 is a sectional side 35 elevation of the credit-accounting appliance in open position and with sundry of the bill holders folded back to gain access to a particular bill holder; Fig. 4 is an enlarged perspective view of part of the rack showing 40 the bill holders in closed position; and Fig. 5 is a similar view of the same showing sundry of the bill holders folded back to display a desired bill holder.

The credit-accounting appliance is provided 45 with a receptacle, preferably made in two sections A, A', connected with each other at adjacent sides by hinges B to permit of swinging one section on top of the other with a view to close the receptacle and 50 the sections A and A'. An index C in the form of a cover is connected by hinges D with the side of the section A provided with the hinges B, to permit of swinging the index C into the open top of either section A 55 or A', at the time the sections are in open position, as shown in Fig. 1, it being under-

stood that when the sections are in closed position, as shown in Fig. 2, then the index C is intermediate both open tops of the sections A and A'.

Each of the sections A and A' is provided 60 with one or more transverse partitions E, dividing each section into a series of compartments, and in each compartment is arranged a rack F consisting essentially of a corrugated base F' and bill holders F², connected at their lower ends by hinges F³ with the upper edges of the corrugations of the base F'. Each bill holder F² is provided at its upper or free end with an integral angular flange F⁴ adapted to rest on the face of the next following bill holder, so that the bill holders are held spaced apart and approximately parallel to each other when in normal or folded position, as shown 65 in Fig. 2. The first pivoted bill holder F² in the upper portion of the compartment rests on a bill holder F⁵ fixed in the compartment and preferably forming an extension of the corrugated base F' of the rack F, 70 and the last bill holder in the lower portion of a compartment is spaced a distance from the lower end of the compartment to permit of swinging any number of adjacent bill 75 holders toward the lower end and into an inclined position to gain access to any one of the bill holders F², as will be readily understood by reference to Figs. 1, 2, 3 and 5. It will be understood, by reference to Figs. 1, 3 and 5, that the bill holders F² 80 in either position rest one against the other, so that the bill holders need not be supported by the user of the device when swinging some of the bill holders toward the lower end to gain access to a particular bill holder, 85 as in both positions the bill holders are inclined and supported one upon the other.

Each face of the index C is provided with a number of ruled columns G, corresponding 90 to the corresponding number of compartments in a section A or A', it being understood that when the index C is swung into the open top of a section A', the now uppermost face of the index C contains as many columns G as there are compartments 95 in the section A, and the other face of the index C contains as many columns G as there are compartments in the section A' of the receptacle. Each of the columns G is provided with a name heading H, and the 100 columns contain the names of the customers, and opposite each name is arranged an

indicating character I, and the indicating characters for each column are preferably in the form of consecutive numerals, as will be readily understood by reference to Fig. 1, 5 the numerals corresponding to similar indicating characters I' arranged on the upper ends of the bill holders F² in a corresponding compartment. A bill K with the name of the customer thereon as well as the name 10 of the merchandise and the price of the purchase is placed on a bill holder F², having the same indicating character I' as corresponds to the indicating character I opposite the name of the particular customer on 15 the index, it being understood that the bill K is placed on the face of the plate holder F² and located in the compartment corresponding to the column in which the customer's name is located on the index. When 20 the bill holders F² are in closed position none of the bills K are visible, and when some of the bill holders F² are folded down toward the lower end of the receptacle then only the bill of the particular customer is 25 displayed at the time, while the others remain concealed, and consequently a customer present at the time cannot see the accounts of other customers. As the successive bill holders F² are spaced apart owing to the 30 flanges F⁴, it is evident that sufficient space is provided between adjacent bill holders to accommodate the bills, and it will also be noticed that by having the flanges F⁴ on the upper ends of the bill holders F² a bill can- 35 not pass out of place when swinging one section of the receptacle onto the other. It will further be noticed that by the arrangement described it is not necessary to provide holding means for the bills, as the same 40 cannot get out of position unless removed by the salesman or other person in charge of the appliance. The names of the customers are preferably alphabetically arranged in the columns G, it being under- 45 stood that the names indicated on the upper face of the index C at the time the latter is in position in the open top of the section A' correspond to the bills in the bill holders F² in the section A, and the names of the cus- 50 tomers on the other face of the index C correspond to the bills contained on the bill holders F² in the section A'.

It is understood that the index C fits into the open top of either section A or A' and 55 is adapted to rest on top of the partitions E, and the index C forms a support for the free ends of the bill holders F² contained in the uppermost section at the time the receptacle is closed and one section is on top 60 of the other (see Fig. 2).

It is understood that when the bill holders F² are in folded position, their upper edges are below the partitions E, and the upper edges of the partitions E are below the tops 65 of the sections A and A' to provide space

for the accommodation of the index C. It will further be noticed that when the sections A and A' are in an open position the the index is firmly supported on either sec- 70 tion A or A', and the customers' names for either section A' or A are displayed to en- able the salesman in charge to readily find a customer's bill, and, if necessary, to re- move the same and place it on the index C for writing additional charges on the bill, 75 and returning the same to the proper place. Thus the index is temporarily used as a writing desk. It should be further pointed out that by corrugating the base F¹ of the bill holder, each corrugation of which forms 80 the bottom of one of the bill holding sec- tions, the said base may be made in one piece and the bills placed loosely therein, without danger of their edges being caught by the hing- 85 es above, thus obviating the necessity of any special bill fastening means.

Having thus described my invention, I claim as new and desire to secure by Letters Patent:

1. A credit-accounting appliance, com- 90 prising a receptacle made in sections hinged together to close one on the other, an index hinged on one of the sections and adapted to form a cover for either section, the said index containing the names of the customers 95 and indicating characters opposite the said names, and a rack in each of the said sec- tions and comprising a corrugated base and bill holders hinged on the said base and pro- 100 vided with indicating characters correspond- 100 ing to those on the said index, each bill holder being provided at its upper free end with an angular flange for holding the bill 105 holders spaced apart and for retaining sales slips in position.

2. A credit-accounting appliance, com- 110 prising a receptacle, an index hinged on the said receptacle and adapted to form a cover for the same, the index containing the names of the customers and indicating characters 115 opposite the said names, and a rack in the said receptacle and comprising a corrugated bottom, and bill holders hinged at their lower ends to the upper edges of the corrugations of the said base, the free ends of 115 the said bill holders being provided with angular flanges for holding the bill holders spaced apart and for retaining the sales slips in position.

3. A credit-accounting appliance, com- 120 prising a receptacle made in sections hinged together to close one on the other, the sec- tions having partitions forming separate compartments, an index in the form of a 125 cover hinged on one of the sections and adapted to be swung into the open top of either section when the sections are in open position, each face of the index having a series of columns corresponding to the num- 130 ber of compartments in the corresponding

section, and each column being provided with indicating characters, and a rack held in each compartment and comprising a corrugated base and bill holders hinged on the 5 base, each bill holder having an angular flange at the rear of its free end and an indicating character at its front face.

In testimony whereof I have signed my name to this specification in the presence of two subscribing witnesses.

ANTOINE LOUIS LAMBERT.
